UNITED STATES PATENT OFFICE.

ARTHUR A. BOUTON, OF BROOKLYN, NEW YORK.

SEWING-MACHINE.

1,383,976.

Specification of Letters Patent. Patented July 5, 1921.

Application filed March 9, 1920. Serial No. 364,372.

To all whom it may concern:

Be it known that I, ARTHUR A. BOUTON, a citizen of the United States, and a resident of the city of New York, borough of Brooklyn, county of Kings, city and State of New York, have invented an Improvement in Sewing-Machines, of which the following is a full, clear, and exact description.

My invention relates to that class of sewing machines in which the work is supported and presented to the needle of the sewing mechanism, upon a traveling carriage and has particular reference to the carriage construction and its associated parts.

In sewing machines of the character described the work supporting carriage is adapted to traverse a track or support on the front of the machine with the work carried thereby successively presented to the sewing mechanism *per se* and in the same plane as the said mechanism. It so happens that this heretofore employed manner of supporting the carriage is inadequate to meet the demands of efficient production for instance the carriage track or support often permits a sidewise wabbling of the carriage resulting in a defective stitch, then again the track or support which is usually made up of a series of rollers becomes worn and the work is not presented to the sewing mechanism in straight lines. With even these slight variations in the travel of the carriage the efficiency of the machine and operation is effected.

It is the purpose of my invention to overcome these many disadvantages as well as to provide means which will offer a maximum of conveniences to the operator.

In the accompanying drawings I have illustrated the preferred embodiment of the invention in connection with a conventional type of machine which has been only slightly modified to accommodate the improvements.

In said drawings,

Figure 1 is a front elevation of a machine embodying the features of my invention.

Fig. 2 is a plan view of the carriage with its associated parts as removed from the machine.

Fig. 3 is a side elevation, and

Figs. 4 and 5 are cross sectional views on the lines 4-4 and 5-5 respectively of

Fig. 1.

Referring to the drawings by letters of reference, 1 is a sewing machine which is

of a conventional type in so far as concerns its general construction. However certain details have been modified to accommodate the invention. The machine 1 may be supported on a table or any other suitable support 2, and driven by a belt or the like 3. The invention finds expression in connection with that type of sewing machine in which the needle is mounted for horizontal reciprocation. The same will be observed as presented on the front of the machine. The same general principle of operation applies to a machine equipped according to my invention as in the type heretofore employed in that the work is supported on a carriage 5 and successively fed past the sewing mechanism. These carriages are usually constructed with a plurality of clamps 6 between the confronting faces of which the work is confined with the portion thereof to be sewed extending slightly above the edge of the clamps. The carriage is driven by the vertical spindle 7 on which is mounted the toothed gear 8 the teeth of which are made to mesh with the rack bar 9 on the inner face of the carriage. Accordingly the rotary motion of the spindle 7 will be converted into a sliding or longitudinal movement of the carriage. Consequently the work confined by the clamps 6 will be successively presented to the sewing mechanism.

Now it is absolutely necessary to insure proper results that there be no wabbling or other loose motion in the carriage 5 as it travels in front of the sewing mechanism. For instance should the carriage wabble sidewise a defective stitch will result and should it not travel with the goods supported in the proper plane the needle will be unable to perform its function. It is customary of course to support the carriages on a track and over which they travel. These tracks have proven inadequate and often produce a wabbling motion in the carriage. Most of the tracks thus far devised are provided with rollers and it is thought these rollers are more or less the cause of the disadvantages experienced with the carriages. I therefore propose to do away with the rollers on the track and to use in their stead a perfectly plain smooth surface and instead of employing a relatively short arm as has heretofore been the case I find that by extending the arm on both sides of the machine and thus offering an elongated surface as a

support for the carriage I am able to realize a more efficient operation. Therefore according to the preferred embodiment of my idea a track 10 comprises an angle iron structure horizontally supported and mounted to the front of the machine in any suitable manner preferably by the screws 11. As this track is rigidly supported and as there are no movable parts on the surface thereof 10 on which the carriage travels the chances of an uneven travel of the carriage thereof are reduced to a minimum.

I have also departed somewhat from the exact construction of the carriage in so far 15 as concerns the construction of the skid or shoe thereof, and the manner of manipulating the clamps 6. To begin with the handles 12 of the clamps have usually been pivoted on the front face of the back plate. Now it 20 is found expedient to extend the handles through the back plate and pivot them as at 13 on the opposite face of the back plate. This will enable a more effective leverage to be realized than has heretofore been found 25 possible when they were pivoted on the front face of the plate. It will be observed that the handles are provided with transverse pins 14 which bridge the slots 15 in the clamps through which the free extremities 30 of the handles extend whereby upon upward movement of the free end of the handles relative separation between the upper extremities of the clamps and the back plate will be effected to permit of the insertion of the 35 work therebetween. The bottom of the clamp 6 is fixed to the back plate by screws or in any other convenient means capable of making a permanent connection between the parts without limiting the flexibility of the 40 clamping end of the clamps. The shoe 16 of the carriage is longitudinally divided into an upper and lower portion, the parts being screwed together by machine screws or the like 17. The shoe is mounted to the carriage 45 5 by the machine screws 18. It will be appreciated that the bottom part of the shoe may be removed and a shim or plurality of them may be inserted between the two parts as at 19 to take up wear on the under face of 50 the lower part of the shoe, the purpose of which will be understood on a further reading of the description.

One of the features of the invention resides in normally confining the carriage on 55 the track so that the same may be readily moved thereon away from the machine when the occasion demands. This is an advantage which the operator will often resort to in her work and can not be realized in the present machines. To effect this condition just mentioned I would prefer to impose a thrust 60 on the shoe of the carriage which would have a tendency to push the same toward the machine and against the vertical side of the track. The means for producing this thrust

preferably comprises a skid 20 which is mounted to an angular clip 21, which projects over the shoe 16 upon which it is adapted to bear for maintaining the same on the track 10. Fixed to the clip 21 is an arm 22 70 the opposite end of which is pivoted as at 23 to the underside of the track 10. The arm is provided intermediate its ends with a hook or the like 24 to which is attached a contractile spring 25, the opposite end of 75 which is secured to a short rod 26 which is adjustably fastened or anchored to a post 27, the post having an opener through which the rod extends and with an axial set screw 80 adapted to bear against the rod and maintain it in any adjusted position to the post. It will now be seen that the spring 25 acts as a tension device for the arm 22 whereupon under the influence of the same the arm with the clip 21 mounted on the end thereof will 85 impart the desired thrust on the shoe of the carriage and support the same in a manner whereby the influence of the spring may be overcome and the carriage radially pulled away from its normal position on the track. 90 A suitable catch 28 which is pivoted as at 29 with a downwardly presented finger 30 on one end thereof is made to extend through an opening in the edge of the track and be received in an opening in the arm 22 for arresting the influence of the spring 25 when the carriage is radially pulled away from the machine thus maintaining the thrust inducing means inactive.

A rest 31 is supported on the table 2 for 100 use in lining the carriage up on the track 10 when presenting the carriage in the machine.

Having thus described my invention, what I claim as new and desire to secure by Letters Patent is as follows:—

1. In a sewing machine, the combination of a work supporting carriage, a track on which said carriage is adapted to travel to present the work supported thereby to the sewing mechanism of the machine, said track comprising a horizontally disposed base provided at its inner edge with an upstanding vertical flange mounted intermediate its ends to the sewing machine with the flange disposed toward the same, a shoe on the carriage adapted to rest upon the horizontal base for longitudinal movement thereon, tension means for normally maintaining the inner side of the shoe against the flange for guiding the same on the track, said means comprising an arm pivoted to the underside of the horizontal base, a clip secured to the free end thereof and adapted to engage the outer side of the shoe, and means for yieldably drawing the arm toward the upstanding flange as and for the purpose specified.

2. In a sewing machine, the combination of a work-supporting carriage, a track on which said carriage is adapted to travel to present the work supported thereby to the

- sewing mechanism of the machine, said track comprising a relatively long shelf mounted in a horizontal plane to provide an even smooth surface in front of the machine and 40
 5 extending beyond the sides thereof, a guide wall for the track along the rear edge thereof, a shoe on the carriage adapted to traverse the said smooth, even surface, and tension means for maintaining the carriage on the 45
 10 track, comprising a pivoted arm, a skid on the arm bearing against the side of the shoe on the carriage, and means associated with said skid and overlying the top of the shoe, and a spring anchored at one end with its 50
 15 opposite end attached to said arm and adapted to maintain the skid against the side of the shoe under tension.
3. In a sewing machine, the combination of a work-supporting carriage, a track on 20
 20 which said carriage is adapted to travel to present the work supported thereby to the sewing mechanism of the machine, said track comprising an angle iron mounted with one of its sides offering a horizontal even surface, its other side providing a guide in the 25
 25 rear edge of the track, a shoe on the carriage adapted to traverse said smooth, even surface, means for maintaining the carriage on the track under tension, comprising an arm pivoted at one end with its opposite end having an angle clip, a skid mounted to said 30
 30 clip adapted to bear against the side of the shoe on the carriage with the horizontal part of said clip overlying the top of the shoe, a spring mounted to said arm with its 35
 35 opposite end adjustably anchored, said skid and clip together with the arm on which they are mounted adapted to normally maintain the carriage in alinement on the track, and
 means associated with the track for over- 40
 coming the influence of the spring when the carriage has been radially displaced on the track.
4. In a sewing machine of the class described, a work supporting carriage comprising a plurality of clamps, a track on which said carriage is adapted to travel to successively present the work supported thereby to the sewing mechanism of the machine, a shoe on the carriage adapted to 50
 45 traverse said track, said shoe comprising a block having a length of substantially that of the carriage and divided longitudinal of the two parts whereby the height of the shoe may be increased or diminished, means for 55
 maintaining the carriage on the track comprising an arm pivoted at one end on the bottom side of the track, an angle clip member on the opposite end of the arm, a skid on 60
 60 said clip adapted to bear against the side of the shoe, said clip having a horizontal part adapted to overlie the top of said shoe, a spring adjustably anchored at one end with the opposite end anchored to said arm for maintaining the skid against the side of said shoe under tension, the tension of said spring adapted to be overcome by a manually radial pull on the carriage whereby the carriage with the goods carried thereby may be 65
 65 moved away from the sewing mechanism 70 and means for arresting the influence of said spring when the carriage has thus been moved, comprising a catch on the front edges of the track, having a finger adapted to be received by an opening in the track 75
 75 and projecting therethrough to engage said arm.

ARTHUR A. BOUTON.
